EGG CONTAINER

Samuel Bergstein, Cincinnati, Ohio, assignor to
 Edna May Bergstein and Robert Morris Berg-
 stein, trustees

Application March 8, 1934, Serial No. 714,678

5 Claims. (Cl. 229—29)

My invention relates to cartons which are made up and stored and shipped in knocked down, partially assembled condition. The particular application of my invention illustrated herein is 5 to cartons for packing and shipping eggs. This carton is of the type comprising a holder for eggs, wherein the eggs are held in two rows longitudinally of the holder, with an inverted channel opening at the lower side of the holder between the two rows of egg compartments, and an outer enclosure, which is the particular subject of my invention, the inner compartment egg holder not being original with me, nor a part 10 of this invention, except as a cooperating element with the novel exterior structure.

One of the objects of my invention is to provide, in a very simple form, a knock-down container of this character which will require only the simplest manipulation by the user to erect 20 it and make it ready for the reception of the inner egg holder with the eggs.

A further object is to provide such a simply constructed container of this character with means formed on its bottom which will extend 25 up into the inverted channel opening at the bottom of the inner egg container to prevent the inner container from sliding out through either end of the outer container. This provision however, is optional, and I am not to be understood 30 as limited to it.

A more particular object, independent of the object just stated, is the provision of the container in its original partially assembled and knocked-down condition in the form of a tube 35 with four walls, the narrow walls constituting side walls and the wide walls being the top and bottom walls, the top wall having an extension such extension being provided, with a middle portion to act as a tuck, to permit the top being opened 40 and reclosed, and the two opposite end portions of the top wall and the middle portion being detachable and fastened to one of the side walls, to retain the tubular condition of the container.

45 Other and more particular objects will appear in the course of the following description illustrated by the accompanying drawings, in which—

Figure 1 is a perspective view of a container embodying my invention, with the partially detached cover portion and its flap raised, and with the inner egg holder partially inserted therein and containing a number of eggs.

Figure 2 is a similar view of the same, with the inner egg holder fully inserted, and with the cover flap portion in closed position.

Figure 3 is a longitudinal vertical section on the line 3—3 of Figure 2.

Figure 4 is a partial bottom plan view of the container.

Figure 5 is a plan of the blank in its initial 5 totally unfolded condition, with the cuts and scores, and its areas to which adhesive is applied, indicated.

Figure 6 is a similar view of this blank when the portions of the blank that are to form the 10 top, including the cover portions and its flap and the portions to which the adhesive is applied are folded over on the narrower rear wall portion and wider bottom portion, with the narrow front 15 extending.

Figure 7 is a similar view when the narrow front portion has been folded back over the flap of the top forming portion, this being the completed knock-down condition of the container.

Figure 8 shows a modified blank having end 20 flaps.

Figure 9 is a partial view of same set up.

Figure 10 shows another modified blank, having complete cuts instead of perforations.

Figure 11 is a partial view of same set up. 25

As I prefer to construct my new improved container, a single sheet of paper stock of the proper weight is cut to have a main rectangular part 1, from one end of which extends a narrower flap 2. This main part 1 is scored at 3, 4, 5, and 30 6, the score lines being so relatively arranged that a narrow front wall 7, a wider bottom 8, a narrower rear wall 9, and a wider top 10, succeed each other in parallel relation, so that when the main portion 1 of the blank is folded on these 35 score lines and these parts 7, 8, 9, and 10 are brought together, the parts form a tube of rectangular cross section.

The part 10, which is to form the top of this tube, has, near its opposite end, lines of perforations 11, not extending to the score lines 5 and 6 that define this top part 10, but instead having at their end parts, cuts 12 and 13 which incline inwardly toward the middle of the blank in their portions nearest to the lines 5 and 6, 45 respectively. These cuts, being entirely through the material and of considerable length, facilitate the tearing of the middle flap portion 14 from lateral edge portions 15 of this top 10. Out past the score line 6 at respective corners of the part 50 10, are extensions 16 which are to adhere to the corresponding corners of the part 7 that forms the front of the tube; and these parts 16 are severed from adjacent portions of the tucking flap 2 at lines 17, so that the flap 2 is entirely free from 55

the adhering portions 16 when the assembly is completed. The tucking flap 2 is preferably tapered with its corners round, as is usual in the formation of flaps for cartons. In its middle, 5 next to the score line 6, this tucking flap 2 has a cut forming a locking tongue 18 with tabs 19. This tongue may be pressed out and when the container is set up it will enter its tabs 19 in slits 20 in the upper part of the front wall 7.

10 The egg holder comprises the middle downwardly converging members 21 and the outward members 22 slanting upward from the bottoms of these middle members 21; all of the four members being pressed to form cavities 23 each approximately the shape of one side of an egg.

15 The central portion of the bottom 8 has cuts 24, each of which consists of an arc-shaped middle cut, the arc-shaped cuts having their concave side presented toward each other, and the outer 20 cuts extend from the middle curved cuts. Further, a cut 25 joins the curved cuts axially thereto. Also, score lines 26 join the outer ends of the diverging cuts 24, and a score line 27 extends midway between the cuts 24 from one joining cut 26 25 to the other.

20 The result of these cuts and score lines is to form flaps 28, each adapted to be bent upward from the bottom 8 on its respective score line 26, and to partially collapse in its score line 27, so 30 that its side portions diverge from this score line toward the middle of the container; while outer tabs 29, formed by the curved parts of the cuts 24, are adapted to further bend in toward each other in a direction toward the mid length of the 35 container. The purpose of these flaps is to fit into the inverted channel between the two middle members 21 of the egg holder after it has been fully inserted into the container, to prevent it from sliding out of the container; and the tabs 40 29 are forced up between the inner exterior surfaces of opposite egg cavities 23, as best seen in the sectional view of Fig. 3.

45 Figure 6 shows the container partially formed; the tabs 16, having had the adhesive applied to them, being ready to receive the corner portions 16a of the front wall 7 when it is folded inwardly, as is shown in Fig. 7. In this latter condition the container is entirely flat, and may be stored and shipped in a minimum of space and with a 50 minimum of expense for handling and shipping charges.

55 The preferred method of packing the eggs in the container is to fill the egg holder with eggs and slip it endwise into the container, after the latter has been brought from its flat, knockdown condition to rectangular tubular shape. In facilitating this, a light metal channel or trough may be used to hold the egg holder in its set up condition, while the eggs are being inserted in 60 the cavities 23 of the holder. Then, with this trough alined with the tubular container, the holder, filled with the eggs, may easily be slid into the container. This allows very rapid packing of the eggs.

65 It will be noted that this packing does not involve the tearing of the middle cover part 14 from the marginal portions 15; so that the container remains sealed at its cover, avoiding the use of any extra seal, such as has been used on 70 egg cartons of other types. The container blanks may be printed, calling attention to this sealed condition, with the pointers to the lines of partial severance, and directions for opening.

75 The locking tongue 18 may be inserted in the slits 20 either before or after the insertion of the

eggs. This locking tongue 18 may be omitted, as the tucking flap 2 cannot escape from the inside of the front wall 7 to allow opening of the carton of the top, on account of the retention of the middle part 14 by the marginal portions 15, still 5 integral with the part 14 and fastened at 16, 16a to the front wall 7. This construction affords a much greater security of closure than any carton depending upon a simple cover, tucked or locked in the same manner and ready to open if the 10 tuck or lock fails.

The flap 28, tucked up into retentive engagement with the egg holder, makes it difficult to remove the egg holder and its contained eggs. If this is attempted, tearing of these flaps 28 is 15 almost certain; therefore, with the preformed sealed condition of the cover, by its middle part 14 remaining integral with the secured marginal parts 15, and this secure retention at the bottom by the flaps 28, there is substantial insurance 20 against substitution of eggs in the container.

The opening left in the bottom of the package by cutting out and bending up of the tongues 28 admits the fingers while the thumb overlies the 25 top of the package; so that very convenient and safe handling of the package is permitted.

In the modification shown in Figs. 8 and 9, the blank is provided with side walls 7a and 9a, and an end closure 31 with a tucking flap 32 to fold in over the side flaps 30 after these have 30 been folded in, and have its tucking flap 32 tucked in, as seen in Fig. 9, making a complete closure of the ends of the package. The tucking flaps 32 are narrow enough not to extend in past the inner edges of the marginal top parts 15, so that the top 35 opening is not obstructed.

Another method of packing is to tear the cover part 14 open, after the egg holder has been inserted empty, and then place the eggs in the holder through the open top, which then may be 40 closed and fastened as before described.

In the modification shown in Figs. 10 and 11, instead of perforations along the lines 11 as in the first example, complete cuts 11a are formed, continuous with the slanted cuts 12 and 13. Thus, the middle part 14 is severed from the marginal 45 portions 15 when the blank is made.

The sealing advantage and security are not present with this example nor with the method of packing just above mentioned, and in either of these cases a locking tab such as the tab 18 of the first example will be more useful. This blank with complete cuts 11a will be slightly more difficult to work on a carton folding and gluing machine than the blank with only weakened connections between the middle part 14 and the marginal parts 15; but it will have the advantage of economy of material, easy packing and handling, and other advantages mentioned in regard to the first example. Also, this package 50 may be very easily opened.

55 Further, it may be noted that if only very slight junctions of the middle part 14 and marginal parts 15 remain intact, as for instance at the point 33, Figs. 10 and 11, the sealing and security are attained, with easier opening than in the first example, as well as making the blank just as easy to work on the folding and gluing machine.

60 My improved construction has advantages in 70 manufacture, in that, after the blanks are cut and creased, they are readily completed on a standard carton gluing machine. As the blanks are moved one by one from the hopper of this machine, the flap or tuck panel 2 is lifted and 75

folded inwardly, leaving the two extensions 16 extending. It is thus possible, with untimed mechanism and untimed glue wheel and the carton traveling in the direction of its length, 5 to deposit adhesive. The middle flap portion 14 is folded inwardly either with the flap panel 2 retained in folded state, or by discontinuing to hold down this panel 2, it will spring open so that when the top portion 14 is folded over, the panel 10 2 will not be retained in its previously folded state. In either case by then folding inwardly the front wall 1, the small portions 16 having the adhesive will become adhesively fastened to this front wall.

15 By my improved design, the carton is produced with a minimum amount of material as well as the minimum cost of production for the reason that a substantially rectangular piece of material is almost entirely used lacking only the small portions 20 at the corners at each side of the tucking flap 2; and owing to the fact that the gluing or adhesive fastening of the carton blank, in its folded condition can be done on a standard high speed carton gluing machine. Owing to the relatively 25 small size of the carton blank, it is possible to print and cut and crease so many more units on a sheet. The economy thus brought about added to the excellent molded cellular egg holder which is available on the market, makes possible a very 30 practical and economical egg container. Although I have rather specifically illustrated and described a preferred example, and have shown several examples of my invention, it will be understood that certain features of one example may 35 be used in another example and that other modifications may occur; and therefore I do not wish to be understood as being limited to the precise disclosure herein, but what I claim as new and desire to secure by Letters Patent is:

40 1. A carton of tubular shape to receive a cellular egg holder, said carton having a tab cut in

its bottom to be turned up therefrom and engage in a recess of the egg holder for the purpose set forth, said tab having a median longitudinal fold which permits it to bend and be crimped into a recess of said egg holder.

2. A carton of tubular shape to receive a cellular egg holder, said carton having a tab cut in its bottom to be turned up therefrom and engage in a recess of the egg holder for the purposes set forth, said tab having lateral projections on its 10 end to bend and make retentive engagement in recesses of the egg holder.

3. A package for eggs comprising in combination; a tubular sleeve, and a formed W-shaped egg holder having pockets each adapted to receive 15 an egg, said tube having a tab in one wall thereof bent into the tube and engaged in the central channel of said holder to prevent relative movement of the holder and tube.

4. A package for eggs comprising in combination; a tubular sleeve, and a formed W-shaped egg holder having pockets each adapted to receive an egg, said tube having a tab with projections at its free end bent into the tube and engaged between adjacent pockets of said W-shaped 20 holder to retain the holder within the tube.

5. A package for eggs comprising in combination; a tubular sleeve, and a formed W-shaped egg holder having pockets each adapted to receive an egg, said tube having a tab with projections at its free end and a central weakened line, said tab being bent into said tube and into locking engagement with said W-shaped holder, said tab being bent upon itself along said score line to fit into the central channel of said holder, 30 and said projections being forced into the space between adjacent pairs of said pockets to lock therewith and retain said holder from endwise movement in said tube.

40 SAMUEL BERGSTEIN.
